UNITED STATES PATENT OFFICE.

CHARLES E. BENHAM, OF SCHENECTADY, NEW YORK.

KEYBOARD FOR COMPOSING-MACHINES.

1,099,734.

Specification of Letters Patent.

Patented June 9, 1914.

Application filed August 8, 1913. Serial No. 783,699.

To all whom it may concern:

Be it known that I, CHARLES E. BENHAM, a citizen of the United States, residing at Schenectady, county of Schenectady, State of New York, have invented certain new and useful Improvements in Keyboards for Composing-Machines, of which the following is a specification.

The present invention relates to keyboards of so-called composing machines and in particular to key boards of machines of the Lanston monotype system although it is not necessarily limited thereto. I shall, however, describe my invention with reference to such machines because it is particularly applicable thereto.

The key board of the Lanston machine is provided with a large number of keys representing various characters which are first depressed and then quickly released by the operator in order to cause the punches corresponding to the characters to perforate the paper, which paper is subsequently used in the casting machine. Among these are the so-called quad, leader and dash keys which for some classes of work, particularly for tabular composition have to be operated a great many times in succession. In some of this composition only a single word occurs in the line, the remainder being filled out with quads, leaders or dashes, as desired. In any event, the same key, be it the quad, leader or dash, must alternately be depressed and released by the operator until the complete line for the page to be printed is filled. This not only requires considerable time and effort on the part of the operator but is exceedingly monotonous. At the present time the fastest method in practice for "quadding out", as it is called, is for the operator to depress and release a key with one hand on one key board and to repeat the operation with the other hand on the other key board, said operations always taking place successively.

My invention has for its object to improve the construction of key boards for the Lanston and similar machines by the introduction without substantial change or rebuilding of what may be designated as a "repeating key" which, when moved by the operator to a given position and retained, as distinguished from a movement first in one direction and then in another, will cause some part of the normal operating mechanism to repeat its action indefinitely until said key is

released or restored to place, and in addition cause the paper ribbon to advance step-by-step and the normal coöperating parts to move between said operations in the usual manner. To state the matter briefly and in another way, my aim is to provide an attachment which can be applied to existing standard key boards whereby a repetition of certain actions necessary to the common and well known use of the apparatus for record making can be effected by the depression and release of a predetermined key.

A further object of the invention is to increase the speed of operation of the machine due to the repeating key to a point considerably in excess of that possible when the operator must first depress and then release the key, as in the present construction.

Other features of my invention will be referred to hereinafter and also set forth in the claims.

In the accompanying drawing which is illustrative of my invention, Figure 1 is a perspective view of a part of Lanston key board fitted with my repeating key; Fig. 2 is a detail view of the valve that controls the motor of the paper feed, and Fig. 3 is a view of a slight modification showing two repeating keys.

I have purposely omitted many of the parts of the machine because they seem unnecessary to an understanding of my invention.

4 indicates one of the many normal operating keys and may represent any desired letter or character, for example as with present case a quad, leader or dash. This key like the others is depressed by hand and then released for each complete operation of the punches which perforate the paper, said paper being later used in a casting machine to form type. The key includes a bell-crank lever 5, the lower end of which engages a projection on the top of key bar 6. On the under side of the bar are two projections that are adapted to engage and move forward the rods or members 7 and 8 that are secured to rock-shafts 9 and 10 respectively. The rods extend parallel to each other from side to side of the key board and may be acted upon by more than one key bar. In addition to the rods 7 and 8 are short rods 11 and 12 also carried by the rock shafts. Situated below the short rods 11 and 12 are valve rods 13 and 14 that actuate the valves 15 and 16 contained in the compressed air

chest 17. Motion from the rods 11 and 12 to the valve rods is transmitted through projections 18 on the latter.

The valve chest is connected by pipes 19 to cylinders containing pistons 20 which force the piston levers 21 upward about their fulcrum 22 whenever the valves are opened by depressing the key 4. The two motors and punch bars shown are typical illustrations of these devices of which a large number is provided for each machine. To each piston lever is attached a bar 23 that carries a punch 24 at its upper end for making holes in the paper ribbon 25. The upper ends of the punches are directed by the guide 26. Above the guide and separated therefrom by a space for the paper is a perforated die plate 27 into which the punches extend when elevated. The paper is carried by a reel 28 and has perforations 29 on its sides to receive pins on the feed rolls 30, on one end of which is a ratchet wheel 36. The marginal perforations 29 are made in the ribbon before it is inserted in the machine, and the pins on the rolls entering the perforations act to properly feed said ribbon step-by-step and also hold it against sidewise movement. Mounted on an arm 37 that is loosely supported on the shaft is a pawl 38 which is moved between punching operations by an amount substantially equal to the pitch of the teeth on the ratchet to feed the paper. 39 indicates a pivoted dog to hold the ratchet while the pawl is retracted.

As before stated the pistons 20 elevate the punch bars and punches. Acting in opposition thereto is a piston 40 which opposition is, however, overcome by the force of the two pistons 20 working against it. The piston 40 which is under constant air pressure is connected to what is generally called a tension arm 41, the latter being rigidly mounted on and oscillating with the rock shaft 42. Connected to the tension arm member by a link is a lever 43 that assists in the operation of the so-called unit-rack slide.

44 indicates a lever that is connected to 50 the stop mechanism, the latter coöperating with a stop for the unit-rack slide.

The means for feeding the paper roll between punch operations will now be described. To the pawl carrying arm 37 is attached a rod 45 whose lower end is connected to the vibrating lever 46. This lever is actuated by two pistons 47 and 48 subject to the control of a valve 49 as best shown in Fig. 2. Normally the left hand end of the lever 46 is raised, that is to say, when the machine is at rest. On the end of the shaft 42 is an arm 50 having a cam slot 51 in which is located a roller 52, said roller being mounted on and moving the lever 53. 60 The lever is fulcrumed midway its ends and

at the lower end is attached to the slide valve 49, the latter having two positions. Air under pressure is admitted to the valve casing by the pipe 54, and its ports 55 and 56 are connected respectively to the cylinders of pistons 47 and 48. The face of the valve has a recess 57 arranged to connect one port or the other with the exhaust opening 58.

Thus far I have described parts which are old and in common use, and before describing my invention as applied thereto, it is desirable to fully understand their action in order that the significance of the added parts will be fully appreciated. The key 4 is depressed by the operator, which causes the punches to rise due to the action of the pistons 20 under the control of valves 15 and 16. This action turns the shaft 42 clockwise by a limited amount, and the arm 50 thereon acting through the cam slot 51, roller 52 and lever 53 moves the valve 49 from right to left. The result of this is to exhaust the air from under the piston 47 and admit air pressure under the piston 48. 90 The left hand end of the lever 46 and pawl actuating rod 45, which were in their raised position are now depressed and the pawl 38 is in position to advance the paper feed roll on the next upward stroke of the rod 45. 95 The operator then releases the key 4 thereby permitting air to escape from under the pistons 20. This permits the piston 40 to force the left hand end of the tension arm 41 down to the position shown and at the same time move the arm 50 with its cam slot, the latter returning the valve 49 to the position shown. This last action causes the piston 47 to push the rod 45 upward and, by moving the pawl, advance the ratchet 100 wheel and feed roll one step. This is the action which normally takes place each time the ordinary key is depressed and released whether it represent a letter, a figure, a quad, a leader, dash or other character. 110

In some cases, as for example with the quad key, it is common practice to omit the punch from one or more of the bars 23, because certain characteristics of the casting machine, and in particular as regards the means for moving the matrix case, render it unnecessary to perforate the paper for this character. Each bar and lever 21, however, move up and down for each operation of its associated key and the ribbon is advanced 115 step-by-step between operations as in other cases, and hence the operation, except for the punch perforating the ribbon, is identical in all cases. 120

Coming down to a description of my invention as applied to a particular machine, a repeating key 60 is mounted on one of the key boards. In many boards a space will be found therefor in the lower right hand corner of the right bank. The key which 130

resembles the others in general appearance acts on a push rod 61, said key and rod being removable with the key bank. The upper end of the push rod enters a hole in the 5 small lever 62, said lever being pivotally supported on the frame above the key bank. To the other end of the lever is attached a slack wire cord or fine chain 63, which is connected at its upper end with a slack wire 10 cord or chain 64, the latter passing on pulleys 64^a supported by the frame of the machine. One end of the cord or chain 64 is connected to the right hand end of the lever 46 and its other end is divided into two 15 parts 65 and 66 which are connected to the rock shafts 9 and 10 in some suitable manner, as by the rods 7 and 8, so that when turned slightly to the right they will operate the valve bars 13 and 14 and the valves 15 and 20 16 controlling the punches. It is important that the connection, whatever it may be, shall normally be slack so that rock-shafts 9 and 10 can be moved forward by the normal keys, represented by 4 and returned 25 without interference therefrom. To state the matter in another way, the connection between the lever 46 and the rock shafts contains lost motion. The cord 64 is connected to the two rock shafts because in this 30 machine two punch bars 23 commonly work together in order to make the proper kind of paper ribbon for the casting machine. In the case of a machine requiring only one punch bar to be operated at a time the cord 35 64 would only have to be connected to one valve bar actuator such as 9 or 10.

The operation of my repeating key 60 is as follows: It is depressed by the operator to the end of its downward stroke which 40 may be determined by a stop of any character and located at any suitable point. The adjustable screw 67 is such a stop. This pushes the rod 61 upward and places the cord 63 under sufficient tension to first take 45 up the slack in the cord 64 and its branches 65 and 66 and then to move the rock shafts 9 and 10 by an amount sufficient to open valves 15 and 16. As soon as this takes 50 place the pistons 20 force the punch bars upward and move the left hand end of the tension arm 41 upward and with it the arm 55 containing the cam slot 51. This latter shifts the valve 49 from right to left with the result that the feed rod 45 is moved down and the right hand end of lever 46 up. This 60 same action relieves the tension on the cord 64 and its branches due to the upward movement of the right hand end of the lever 46. This permits the rock-shafts to be moved backward; the compressed air in the chest 65 acting on the valves 15, 16 and valve bars 17 has sufficient power to do this. At this instant the piston 40 and tension arm 41 come into play and depress the punch rods. This in turn rocks the shaft 42 and arm 50 anticlockwise with the result that the arm which was elevated is now depressed to the position shown and the valve 49 which was in its left hand position during the punching operation is now moved to the right as 70 in Figs. 1 and 2. This position of the valve exhausts the air from under piston 48 and admits air pressure under the piston 47. Immediately the left hand end of the lever 46 jumps upward causing the rod 45 to actuate the paper advancing ratchet 37 and the toothed rollers 30. This same action depresses the right hand end of the lever 46 which first takes up the slack in the cord 64 and its branches 65 and 66 and then pulls 75 the rods 7 and 8 on the rock shafts by an amount sufficient to again actuate the valve bars 13 and the valves 15 and 16. This action goes on indefinitely so long as the repeating key 60 is held down by the operator. 80 Owing to the fact that one or more of the motors act in response to a movement of the repeating key, the feeding mechanism will advance the ribbon between each two similar movements, and hence it makes no difference if a punch has been omitted from a punch bar, providing, of course, as heretofore explained in connection with the matrix case of the casting machine, a punch is unnecessary to the successful operation. 85

Care must be exercised to see that the cord 63 does not strain the actuating cord 64 too much for if it does the rock shafts cannot return automatically to place and permit the valves 15 and 16 to close and also exhaust the 90 air from under the pistons. On the other hand, if strained too little, the downward movement of the right hand end of the lever 46 will not actuate the rock shafts. By experiment the assembler can readily determine the exact relation of parts, either by changing the lengths of the cords or providing a stop to limit the movement of the key 60 or small lever 62, or both methods of adjustment may be employed. 95

The operation of the punches and feeding of the paper is much faster than where the normal keys 4 are depressed and released even though the operator strikes a key first with one hand and another key in the other bank with the other hand. The rapidity of operation is comparable with the movements of the piston of a pneumatic hammer. In order to test the speed of operation of a machine fitted with my repeating key, I had a 100 skilled operator strike and release an ordinary key just as fast as possible for a period of 10 seconds. I then had the same operator hold the repeating key down for the same length of time. As a result, it was found 105 that the punches operated 66 times in the first test and 128 times in the second test, thus showing a large gain in favor of the repeating key. The increased speed of operation is due chiefly to two things: First, 110

115

120

125

130

the operator has only one down and up motion to make instead of many; and second, the work of actuating the valves 15 and 16 is accomplished by a quick acting motor, in 5 this case the pistons 47 and 48. The speed of the machine is determined by the rapidity of action of these pistons and hence by utilizing them to actuate the valves 15 and 16 when the repeating key is moved to a 10 predetermined position, the punching and ribbon feeding operations will take place with a rapidity that is limited only by the capacity of said pistons to properly perform their functions. I have also found that the 15 ordinary operator is able to perform a materially greater amount of work in a given time with my improved key than without it where repetition of characters largely occurs.

An analogy in the electric art to the operation 20 of my improved mechanism can be found in an electric bell. Here when the circuit is closed by a push button the magnet coils are energized and attract the armature against a spring. Shortly after the 25 armature starts, it breaks the circuit of the coils but the armature continues its movements for a short distance due to inertia. Subsequently the spring returns the armature to a position where the circuit of the 30 coils is again closed and the action is repeated.

In Fig. 3 I have shown a slight modification 35 of my invention where two repeating keys are provided. One of these may be for the eighteen unit quad and the other for a leader, dash or other character which occurs frequently and in succession in the pages of matter to be set up and printed. This is of particular advantage in tabular composition 40 where the major part of the line is blank or is filled in with dots or dashes. In this figure the repeating key 60 operates as before. The second repeating key 70 is connected to a lever 71 and the other end of the 45 lever is connected by the slack cord 72 to the slack connector 73, the latter passing over pulleys as before. The lower end of the cord has slack branches 74, 75 that are connected to rock shafts 76 and 77 that are independent 50 of the rock shafts 9 and 10. Either key can be used at will but not both at the same time.

My invention is not necessarily limited to the use of flexible cords and lever 46, although I have found this arrangement to be exceedingly satisfactory in practice. The main thing is to utilize some part of the usual operating mechanism which moves between each two punching operations as for 60 example a part of the ribbon feeding mechanism to do the actual work of opening the valves or moving the equivalent parts to repeat the punching operation, the repeating key and co-operating parts serving as a means 65 to start the automatic operation.

One important feature of my invention resides in the fact that it can be applied to existing machines without rebuilding or change. The parts are merely in addition to those now in daily use and can be applied with very little effort and at a small expense. 70

Another important feature is that each and all of the usual keys can be operated in the ordinary manner without regard to the repeating key. The operator can still "quad out" by the usual key if the space to be filled is small or if large the repeating key can be used. In the use of the repeating key, the operator will, of course, utilize the various devices now on the machines to indicate how much of the line to be printed is to be filled out by quads or other type. 75 80

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means. 85 90

What I claim as new, and desire to secure by Letters Patent of the United States; is,—

1. In an apparatus of the character described, the combination of means for making records on a ribbon between its marginal perforations, motors for actuating the means, mechanism for returning said means and feeding the ribbon between record making operations, and a repeating key which, when moved to a predetermined position, causes the mechanism to start a motor and control its operation. 95 100

2. In an apparatus of the character described, the combination of punches for perforating a ribbon between its marginal perforations, motors for causing the punches to act, a valve for controlling each motor, mechanism for withdrawing the punches and feeding the ribbon between punching operations, and a repeating key which, when moved to a predetermined position, causes the mechanism to move a valve to a position to start a motor and thereafter control its operation. 105 110 115

3. In an apparatus of the character described, the combination of punches for perforating a ribbon between its marginal perforations, motors for actuating them, means acting in opposition to the motors for returning the punches to their normal positions, mechanism which is moved in one direction by the motors and in the opposite direction by said means, controllers for the motors, means which are normally inactive for transmitting motion from the mechanism to certain of the controllers, and a repeating key for rendering the last named means active. 120 125

4. In an apparatus of the character de- 120

- scribed, the combination of a punch bar, a fluid pressure motor for actuating the bar, a controlling valve for the motor, mechanism for returning the bars and advancing the ribbon between bar operations which includes a vibrating member, means normally inactive for transmitting movements of the member to the valve, and a key for rendering the last named means active when it is desired to repeat the action of the bar.
5. In an apparatus of the character described, the combination of motor actuated means for making records on a ribbon between its marginal perforations, mechanism 15 acting automatically between record making operations to return the means to normal position and also to feed the ribbon forward one step, and a key means which, when moved to a given position, starts a motor actuated means into operation and thereafter causes said mechanism to keep it in operation.
6. In an apparatus of the character described, the combination of fluid motor actuated means for perforating a ribbon between its marginal perforations, mechanism acting automatically to return the means and also to feed the ribbon forward one step, a valve controlling a motor, and a key means which, when moved to a given position, opens the valve and causes the motor to act, and means actuated by the mechanism which permits the valve to close during one portion of its complete movement and opens it during the remaining portion of its movement.
7. In an apparatus of the character described, the combination of a punch for perforating a ribbon, punch actuating means, mechanism for feeding the ribbon between punching operations, and means for causing the ribbon feeding mechanism to control the operation of the punch actuating means.
8. In an apparatus of the character described, the combination of a punch for perforating a ribbon, means for operating the punch, a key that normally controls the means, means for withdrawing the punch, a feeding device for the ribbon, a motor for actuating the device, and means whereby the movement of the motor is caused to automatically start the punch operating means into action and release it.
9. In an apparatus of the class described, the combination of a punch bar, means for actuating it, means for retracting it, a ribbon feeding device, a motor for actuating it, a valve for the motor which is controlled by the punch retracting means, a connection between the movable part of the motor and the means for actuating the punch, which has lost motion and is normally idle, and a key for taking up the lost motion and causing the movements of the motor to alternately actuate and release the punch bar actuating means.
10. In an apparatus of the character described, the combination of a punch for perforating a ribbon, punch actuating means, mechanism for feeding the ribbon between punching operations, connection between said means and mechanism that is normally inactive, and a repeating key which when moved to a predetermined position puts said connection into action.
11. In an apparatus of the character described, the combination of a punch for perforating a ribbon, a motor for actuating the punch, a controller for the motor, a key for moving the controller, means for retracting the punch, mechanism for feeding the ribbon between punching operation, which includes a motor, a controller for the motor which is actuated by the punch retracting means, a connector between a movable member of the last mentioned motor and the controller of the first motor which is normally inactive, and a key which when moved to a predetermined position puts the connector into action and co-operates with it to cause said removable member to alternately actuate and release the controller of the first mentioned motor.
12. In an apparatus of the character described, the combination of a punch bar, a fluid motor for actuating the bar, a means for retracting it, a valve for controlling the motor, an actuator for the valve, a ribbon feeding mechanism, a fluid motor for actuating it, a means which is normally inactive and is connected to the valve actuator and to a movable part of the said motor, and a key which when moved to a predetermined position acts on said last named means in a manner to cause movement of the member to alternately actuate and release the valve actuator.
13. An apparatus of the character described, comprising punch bars, motors for actuating them, valves for the motors, actuators for the valves, means for retracting the punch bars, a ribbon feed device, a motor for actuating it, and a valve for the motor actuated by the retracting means, in combination with a slack flexible connector which is connected to the valve actuators and to a movable member of the ribbon feed motor, and a key which when moved to a predetermined position first takes up the slack in the connector and then moves the valve actuators, said member alternately placing the connector under tension and releasing it.
14. In an apparatus of the character described, the combination of means for punching a ribbon, means controlling the operation of the punching means, feeding mechanism for advancing the ribbon between each two operations, a normally inactive means for connecting the ribbon feeding mechanism with said controlling means, and a key which when moved to a predetermined po-

sition puts said connecting means into operation and causes it to transmit movements of the ribbon feed mechanism to and actuate the controlling means.

- 5 15. In an apparatus of the character described, the combination of a punch bar, punch bar actuating means, mechanism for feeding the ribbon between bar operations that includes a motor and a lever vibrated thereby, a repeating key, a slack connector which is secured at one end to the vibrating lever and at the other end to the bar actuating means, and a means actuated by the key for putting the connector under sufficient tension to cause the lever to alternately actuate and release the bar actuating means as it vibrates.

- 10 16. In an apparatus of the character described, the combination of a punch bar actuating means therefor, mechanism for feeding the ribbon between bar operations that includes a fluid motor and a lever vibrated thereby, a repeating key means, a slack connector which is secured at one end to an arm 20 of the lever and at the other end to the punch actuating means, means for supporting the connector at two points, and a second connector that is united at one end with the first at a point between said supporting means and at the other end is connected to the repeating key means.

- 25 17. In an apparatus of the character described, the combination of a punch bar, punch bar actuating means, mechanism for feeding the ribbon between bar operations, and independent repeating key means which when moved individually to predetermined

positions will cause the ribbon feeding mechanism to control the operation of the punch bar actuating means.

- 40 18. In an apparatus of the character described, the combination of punches for perforating a ribbon, punch actuating means, mechanism for feeding the ribbon between punching operations that includes a motor 45 and a lever vibrated thereby, repeating keys, slack connectors therefor which are secured at one end to the vibrating lever and at the other ends to the punch actuating means, and means associated with each repeating key for putting its connector under sufficient tension to cause the lever to alternately actuate and release a punch actuating means as it vibrates.

- 50 19. In an apparatus of the character described, the combination of punch bars, individually acting motors for reciprocating the bars, mechanism for returning the movable parts of the motors and bars and feeding a ribbon forward step-by-step between each 55 two similar movements of a bar or bars, and a repeating key which, when moved to and retained in a predetermined position, causes said mechanism to start a motor and cause successive operations thereof and its corresponding bar between movements of the ribbon feeding mechanism.

In witness whereof I have hereunto set my hand this fifth day of August 1913.
